(57) **CLAIM**

The ornamental design for adjustable spot putting device, as shown and described.

DESCRIPTION

FIG. 1 is a pictorial view of the present invention.

FIG. 2 is a front view of the present invention.

FIG. 3 is a side view of the present invention.

FIG. 4 is a top view of the present invention; and,

FIG. 5 is a bottom view of the present invention.

1 Claim, 5 Drawing Sheets

FIG. 1

FIG. 2

FIG. 4

FIG. 5
